INTERLOCKING SLIDE FASTENER

Benjamin Adler and Lazar Siegel, Brooklyn, N. Y.

Application June 27, 1940, Serial No. 342,676

8 Claims. (Cl. 24—205)

This invention relates to interlocking slide fasteners, and articles, such as bandages, surgical stockings, raincoats or the like, which embody such slide fasteners.

There are many applications, such as surgical stockings, bandages, and a variety of other articles, in which commercially available stretchable rubber or rubber-like sheet materials could be used with great advantage if they could be provided with interlocking slide fastener closures of the Zipper type, that would not detract from the desirable characteristics of the article made of such material.

The interlocking links or teeth of all commercially practical slide fastener closures, familiarly known as Zippers, of the general type described, for instance, in U. S. Patent 1,243,458, have to be mounted in a predetermined, equally-spaced, relation on a tape or stringer provided with a beaded edge which resists stretching to such a degree as to be practically non-stretchable. Otherwise, the staggered interlocking links of such slide fastener are readily brought out of their properly spaced and aligned operative positions, and the fastener loses its utility. As a result, all commercially practical slide fasteners had to be made with mounting tapes having beads of substantially non-stretchable textile fabric, such as cotton.

Heretofore, great difficulties have been encountered in securing or fastening the textile web of such slide fasteners to the closure edges of articles made of rubber-like materials. If the textile webs of such slide fasteners are secured to the closure edge of an article made of such rubber-like material by stitches, the junction not only impairs the appearance of the article, but the edge of the rubber-like material is greatly weakened, and is readily torn off. If the textile web of such slide fastener is cemented to an edge of such plastic sheet material, the junction is likewise unsatisfactory because it lacks the desired flexibility and it readily strips off.

The invention solves the foregoing difficulties by making the tape of such interlocking slide fasteners with a web of rubber-like material which has an affinity, and may be readily united to the closure edges of articles made of rubber-like material, and by integrally forming along the edge of such web a substantially non-stretchable bead on which the interlocking members are clamped in their proper operative spacing.

Included among the rubber-like materials suitable for making slide fasteners of the invention are vinyl chloride resins, commercially known as

Vinylite and Koroseal, poly isobutylene resins, chlorobutadiene resins, commercially known as Neoprene, rubber hydrochloride resins, commercially known as Pliofilm, and synthetic linear polyamide resins.

The foregoing and other objects of the invention will be best understood from the following description of a practical exemplification of the invention, reference being had to the accompanying drawing, wherein

Fig. 1 is a perspective view of a surgical stocking made of a synthetic rubber-like material in accordance with the principles of the invention;

Fig. 2 is an enlarged detailed view of a portion 15 of the slide fastener junction of the stocking of Fig. 1;

Fig. 3 is a cross-sectional view along line 3—3 of Fig. 2;

Fig. 4 is a cross-sectional view similar to Fig. 3 through a tape element of a slide fastener;

Fig. 5 is a view similar to Fig. 3 of another embodiment of the invention; and

Fig. 6 is a perspective view illustrating a portion of the stocking shown in Fig. 1.

In Fig. 1 is shown, as one practical exemplification of the invention, a surgical stocking, for the treatment of varicose veins, for instance. Instead of making the stocking of elastic yarn fabric as usual, it is made of a transparent elastic synthetic rubber-like sheet material, such as the commercially available thin vinyl resin sheet material, sold under the name Vinylite. Stockings of such material have many advantages over stockings made of elastic yarn fabric, not only because it is much more sanitary and more effective in serving its purpose, but also because it may be made so thin and transparent as to enable the user to wear the surgical stocking underneath a silk hose, thus combining the benefit derived from the surgical stocking with the good external appearance of the sheer silk hose. In addition, the difficulties of keeping the stocking in sanitary condition are eliminated because a superficial washing of the surface of the stocking will keep it in highly sanitary condition.

Elastic Vinylite sheet material, and other commercially available similar rubber-like sheet materials, lend themselves for making such stockings. Adjacent portions of such resin sheet material may be readily united into a substantially homogenous sheet structure or unitary lamination by applying a suitable solvent to the overlapping surfaces and pressing them together, or heating and pressing them together, or applying solvent and heat and pressing them together.

Alternatively, such stocking may be made by placing the material while heated to a fluid state rendered fluid by solvents into a suitable mold, the stocking being obtained by solidifying it in the molded shape either by lowering the temperature or by driving off the solvent.

Commercially proven methods of shaping articles, such as stockings, out of such materials, are made available to purchasers by the vendors of such material, and require no further description.

Since the material of the stocking is elastic, the upper open end 10 thereof may be left closed and only the portion of the stocking extending from the ankle up to the knee may be provided with a slit or opening between the adjacent closure edges 11 of the sheet material forming the stocking.

In accordance with the invention, the closure edges 11 of an article made of such elastic sheet material are provided with slide fasteners having their interlocking teeth mounted on a substantially non-stretchable bead formed on the edge of such material.

Although, as explained hereinafter, the closure edges of the article, such as the stocking described above, made of such stretchable material, may, in accordance with the invention, be provided with a non-stretchable bead for mounting thereon the interlocking teeth of the fastener, the commercially more practical slide fastener with a mounting tape of such material will first be described.

In the form shown in Figs. 2 and 3, a slide fastener of the invention has two stringers 13, each formed of a mounting tape 14, provided along its edge with a bead 15 to which are clamped the jaws 16 of a row of interlocking teeth or links 17. The teeth of the two stringers are staggered relatively to each other so that by moving in opposite directions the slider cam 18 fitting over the teeth 17, the stringers are actuated to close and open their interlocking engagement, as in conventional slide fasteners.

The web 20 of the stringer tape 14 is formed not of textile fabric as usual, but of rubber-like sheet material, such as Vinylite, that stretches when exposed to the forces exerted on the interlocking teeth when the slider is actuated to close or open their interlocking engagement. As shown in Fig. 3, a tape strip 14 of such material is folded over a thin core 21 to form the bead 15 to which the jaws 16 of the interlocking teeth 17 are to be clamped. The portion of the tape strip 14 which surrounds the core is reinforced by a strip 22 of relatively non-stretchable material. The reinforcing strip 22 may be of textile fabric or any other material that will, under external forces exerted thereon in opening and closing the interlocking engagement of the teeth, resist stretching that would disturb the operative alignment and regular spacing of the teeth on the bead 15.

By clamping the jaws 16 of the interlocking links 17 around the bead 15 of the stringer tape, so as to firmly engage the relatively non-stretchable strip 22 extending along the exterior of the bead formation, the predetermined equal spacing of the links will be assured notwithstanding the fact that the web 20 of the stringer tape is formed only of the stretchable rubber-like sheet material which is used in forming the bead 15. The strip 22 serves thus as an aligning and spacing element of the bead formation 15. Such aligning and spacing strip 22 may be formed of

any material which, when subjected to stretching forces of the character exerted by the interlocking links when they are actuated between their closed interlocking and open positions, will resist stretching beyond a degree that would disturb the predetermined aligned spacing and bring about mis-alignment of the interlocking links 17 mounted on the bead 15. At the same time, the material of the spacing and aligning strip 22 is of such character as to assure that the jaws 16 of the locking teeth have good clamping engagement therewith and are prevented from longitudinal displacement from their clamped position on the bead 15.

Strong thin commercially available cotton fabric is very economical for use as the material for the spacing and aligning strip 22 of the bead. The core 21 may likewise be made of a similar commercially available fibrous cotton material and is likewise made sufficiently solid so as to form, in conjunction with the exterior spacing and aligning strip 22 and the intermediate layer of the stretchable material, a bead formation which will provide a positive support for the links, while assuring great flexibility of the bead formation between adjacent links 17.

When such cotton or similar fibrous fabric is used for the spacing and aligning strip 22 and the core 21, they are preferably impregnated or saturated with a cementitious material having an affinity for the rubber-like material of the tape strip 20 so that when they are assembled together into a bead formation, in the way shown in Fig. 3, they will be united to each other and form an integrally coalesced body.

Alternatively, the fabric strip 22 may be embedded in the surface of the rubber-like tape 14 while it is flat, and before the bead is formed, the material of the tape being softened so as to permit the fabric strip 22 to be united and embedded within the body of the tape material 14.

As another alternative, a large number of parallel flat strips 22 of non-stretchable material may be embedded in a large sheet of material out of which the tapes 14 are to be cut, while the sheet material of the tape 14 is produced, for instance, by a casting process used in making most of the synthetic rubber-like materials which are suitable for practicing in the invention.

Any cementitious material, forming a firm bond or having bonding affinity to the rubber-like material of the tape 14 may be used for uniting the several elements of the bead 15 into an integral bead formation. If desired, such cementitious material may also be applied to the bead after the links 17 have been clamped in place thereon in order to hold the links more firmly in their properly spaced positions on the bead 15.

Slide fasteners of the invention, such as described above, may be made with interlocking links 17 of metal. However, in many applications, such as in making surgical stockings, the links may be made of a synthetic resin material, and, if necessary, of transparent synthetic resin material.

Instead of using a strip of textile fabric material for the spacing and aligning element 22 of the bead 15, a plurality of longitudinally extending threads of non-stretchable material may be used as the aligning and spacing means for the bead 15 by fusing the threads to the exterior surface of the bead portion of the tape 14 which extends around the bead core 21 and is used for forming the bead. In other words, the trans-

verse welt threads of such fabric strip 22 may be eliminated since the longitudinally extending warp threads are sufficient for performing the spacing and aligning functions of spacing and aligning element 22. A tape with a bead formation of the type described above in connection with Figs. 2 and 3 may be manufactured in a continuous process and in a very economical way.

Instead of using cotton fabric for the spacing and aligning element 22 and the core 21 of the bead formation 15, other materials which have a similar resistance to stretching at normal temperatures, such as silk or Nylon, may be used. By using a transparent synthetic resin material for the relatively non-stretchable spacing and aligning element 22 and the core element 21 as well as for the interlocking teeth 17, and combining them with a tape 14 of transparent elastic, rubber-like, synthetic-resin material, a substantially transparent slide fastener structure may be produced. This is important in producing articles, such as surgical stockings, which should remain inconspicuous when worn on the leg under sheer silk hose, for instance.

The core 21 of the bead may be made of twisted or interwoven strands of fibrous material, or of flexible strands of plastic material, or of flexible wires. When making a tape formation of the type described in connection with Figs. 2 and 3 in a continuous process, the tape formation 14 with the spacing and aligning strip 22 are combined and united in a continuous process while forming the sheet material of the tape. To the so-produced flat tape 14 is fed a cord out of which the core 21 is formed and the flat tape 14 is wrapped around the cord and united thereto by pressure in a suitable guide tool. Heat and pressure or solvent and pressure may be used to fuse the several elements of the bead into an integral body depending on the material used. The various manufacturers of synthetic resin materials, such as Vinylite, Koroseal and rubber hydrochloride, supply with their material the specifications as to the type of cement and the character of the process suitable for fusing and uniting such materials, and the production of a tape 14 having a bead formation 15 of the type shown in Figs. 2 and 3 presents no problems.

A tape stringer of the type shown in Figs. 2 and 3 may readily be secured to a closure edge of an article, such as a bandage or stocking, made of rubber-like material, by uniting the two flaps 20 of the tape 14 to both sides of the closure edge 31 of such material, in the way shown in Fig. 4. The uniting of the web flaps 20 and the closure portion 31 of the sheet into a substantially homogenous sheet structure or unitary lamination may be effected either by heating and pressing them together, if they are of thermoplastic material, or by applying solvent and pressure to their facing surfaces, or applying to their surfaces solvent while subjecting them to pressure or heat and pressure, or by applying to their surfaces a cementitious material while subjecting them to pressure, or pressure and heat, depending on the character of the sheet material or cement used, as specified by the suppliers of such materials.

As shown in Fig. 5, instead of making the stringer tape 14 of the invention with two web flaps 20, it may be made with a single flap 20. The web flap 20 of one of the stringers 14 is united to one closure edge 31 of the article which is to be provided with a fastener, and the web

flap 20 of the conjugate stringer is united to the other closure portion 32 of the article, so as to provide a flap extension 33 underlying the two interlocked rows of the stringer links 17 for keeping them out of contact with the object, such as the leg, which is to be enclosed by the stocking.

The article with the closure edges 31, 32 may, for instance, be the stocking shown in Fig. 1. While in making a surgical stocking of the type shown in Fig. 1 it is commercially cheaper to unite the stringers to the closure edges 11 of the stocking, the edges of an article, such as a bandage, may be themselves used for forming thereof a bead formation in the way described in connection with Figs. 2 to 5.

As shown in Fig. 6, when a stringer tape of the type shown in Figs. 2 and 3 is united to an article, such as a stocking of the type shown in Fig. 1, the end of each stringer tape 14 may be provided with flat end portions 35, 36, which are without a bead and free of the interlocking links, the two flat end portions 35 being utilized to reinforce the adjoining continuous sheet surface 37 of the article, for instance, by integrally uniting the tape end 35 to the outer side of the continuous stocking portion 37 and the other tape end 36 to its inner side, so as to reinforce it at the point where the closure starts.

Although the exemplifications of the invention have been described above in connection with elastic stretchable materials, the invention is also of great value in connection with materials, which, though lacking elasticity, are stretchable, because such stretchable materials would likewise fail to form a satisfactory bead for the interlocking members of the slide fasteners of the type herein described. Accordingly, stretchable material, such as cellulosic derivative materials, are included among the materials to which the invention is applicable.

Many other modifications of the invention will suggest themselves to those skilled in the art. It is accordingly desired that the appended claims be construed broadly and that they shall not be limited to the specific details shown and described in connection with the exemplifications thereof.

We claim:

1. In a separable slide fastener for two closure portions having two cooperating rows of interlocking links which are brought into locking engagement and separated by a slider engaging said interlocking links, a stringer for each row of interlocking links forming the junction between the interlocking links and the associated closure portion, each stringer including an elongated web of pre-formed elastic stretchable rubber-like sheet material and a bead extending along said web to constitute a flexible support clampingly engaged by the associated row of interlocking links so as to hold them in a predeterminedly-spaced operatively-aligned relation, said bead being formed of a portion of the pre-formed sheet material of said web folded over a cord formation and united thereto to constitute a bead formation of a predetermined overall thickness determined by the thickness of the cord formation and the thickness of the pre-formed sheet material folded thereover, said cord formation being substantially nonstretchable and the thickness of the elastic sheet portion folded thereover being sufficiently thin and so united to said cord formation that the bead formation constitutes a substantially nonstretchable support effective in holding the links clamped thereto in their predeter-

minedly-spaced relation notwithstanding the stretchable character of the material of the folded-over sheet portion, and substantially preventing disturbance of the operatively-aligned relation of associated links under the action of forces exerted thereon by the motion of the slider when locking or separating the links.

2. In a separable slide fastener for two closure portions having two cooperating rows of interlocking links which are brought into locking engagement and separated by a slider engaging said interlocking links, a stringer for each row of interlocking links forming the junction between the interlocking links and the associated closure portion, each stringer including an elongated web of pre-formed elastic stretchable rubber-like sheet material forming two portions having inwardly facing surfaces and a bead extending along said web to constitute a flexible support clampingly engaged by the associated row of interlocking links so as to hold them in a predeterminedly-spaced operatively-aligned relation, said bead being formed of an intermediate portion of the pre-formed sheet material of said web folded over a cord formation and united thereto to constitute a bead formation of a predetermined overall thickness determined by the thickness of the cord formation and the thickness of the pre-formed sheet material folded thereover, said cord formation being substantially nonstretchable and the thickness of the elastic sheet portion folded thereover being sufficiently thin and so united to said cord formation that the bead formation constitutes a substantially nonstretchable support effective in holding the links clamped thereto in their predeterminedly-spaced relation notwithstanding the stretchable character of the material of the folded-over sheet portion, and substantially preventing disturbance of the operatively-aligned relation of associated links under the action of forces exerted thereon by the motion of the slider when locking or separating the links.

3. In an article, such as a surgical stocking, having two closure portions of elastic stretchable rubber-like sheet material, a separable slide fastener for said two closure portions having two cooperating rows of interlocking links which are brought into locking engagement and separated by a slider engaging said interlocking links, a stringer for each row of interlocking links forming the junction between the interlocking links and the associated closure portion, each stringer including an elongated web of pre-formed elastic stretchable rubber-like sheet material overlapingly joined to the associated closure portion and a bead extending along said web to constitute a flexible support clampingly engaged by the associated row of interlocking links so as to hold them in a predeterminedly-spaced operatively-aligned relation, said bead being formed of a portion of the pre-formed sheet material of said web folded over a cord formation and united thereto to constitute a bead formation of a predetermined overall thickness determined by the thickness of the cord formation and the thickness of the pre-formed sheet material folded thereover, said cord formation being substantially nonstretchable and the thickness of the elastic sheet portion folded thereover being sufficiently thin and so united to said cord formation that the bead formation constitutes a substantially nonstretchable support effective in holding the links clamped thereto in their predeterminedly-spaced relation notwithstanding the stretchable charac-

ter of the material of the folded-over sheet portion, and substantially preventing disturbance of the operatively-aligned relation of associated links under the action of forces exerted thereon by the motion of the slider when locking or separating the links, the materials of said web and the material of said closure portions having similar elastic and bonding characteristics, and the facing portions of said web and said closure portion being united to each other over a continuous junction area so that the region of the junction between the web and the closure is formed of material having substantially the same characteristics.

4. In an article, such as a surgical stocking, having two closure portions of elastic stretchable rubber-like sheet material, a separable slide fastener for said two closure portions having two cooperating rows of interlocking links which are brought into locking engagement and separated by a slider engaging said interlocking links, a stringer for each row of interlocking links forming the junction between the interlocking links and the associated closure portion, each stringer including an elongated web of pre-formed elastic stretchable rubber-like sheet material forming two portions having inwardly facing surfaces overlapingly joined to the exterior surfaces of the associated closure portion and a bead extending along said web to constitute a flexible support clampingly engaged by the associated row of interlocking links so as to hold them in a predeterminedly-spaced operatively-aligned relation, said bead being formed of an intermediate portion of the pre-formed sheet material of said web folded over a cord formation and united thereto to constitute a bead formation of a predetermined overall thickness determined by the thickness of the cord formation and the thickness of the pre-formed sheet material folded thereover, said cord formation being substantially nonstretchable and the thickness of the elastic sheet portion folded thereover being sufficiently thin and so united to said cord formation that the bead formation constitutes a substantially nonstretchable support effective in holding the links clamped thereto in their predeterminedly-spaced relation notwithstanding the stretchable character of the material of the folded-over sheet portion, and substantially preventing disturbance of the operatively-aligned relation of associated links under the action of forces exerted thereon by the motion of the slider when locking or separating the links, the materials of said web and the material of said closure portions having similar elastic and bonding characteristics, and the facing portions of said web and said closure portion being united to each other over a continuous junction area so that the region of the junction between the web and the closure is formed of material having substantially the same characteristics.

5. In an article, such as a surgical stocking, having two closure portions of elastic stretchable rubber-like sheet material, a separable slide fastener for said two closure portions having two cooperating rows of interlocking links which are brought into locking engagement and separated by a slider engaging said interlocking links, a stringer for each row of interlocking links forming the junction between the interlocking links and the associated closure portion, each stringer including an elongated web of pre-formed elastic stretchable rubber-like sheet material overlapingly joined to the associated closure portion

and a bead extending along said web to constitute a flexible support clampingly engaged by the associated row of interlocking links so as to hold them in a predeterminedly-spaced operatively-aligned relation, said bead being formed of a portion of the pre-formed sheet material of said web folded over a cord formation and united thereto to constitute a bead formation of a predetermined overall thickness determined by the thickness of the cord formation and the thickness of the pre-formed sheet material folded thereover, said cord formation being substantially nonstretchable and the exterior of the folded-over elastic sheet portion overlying said cord formation embodying longitudinally extending elements exhibiting sufficiently greater longitudinal stretch resistance than the adjacent elastic sheet portion that the bead formation constitutes a substantially nonstretchable support effective in holding the links clamped thereto in their predeterminedly-spaced relation notwithstanding the stretchable character of the material of the folded-over sheet portion, and substantially preventing disturbance of the operatively-aligned relation of associated links under the action of forces exerted thereon by the motion of the slider when locking or separating the links, the materials of said web and the material of said closure portions having similar elastic and bonding characteristics, and the facing portions of said web and said closure portion being united to each other over a continuous junction area so that the region of the junction between the web and the closure is formed of material having substantially the same characteristics.

6. In an article, such as a surgical stocking, having two closure portions of elastic stretchable rubber-like sheet material, separable slide fastener for said two closure portions having two cooperating rows of interlocking links which are brought into locking engagement and separated by a slider engaging said interlocking links, a stringer for each row of interlocking links forming the junction between the interlocking links and the associated closure portion, each stronger including an elongated web of pre-formed elastic stretchable rubber-like sheet material forming two portions having inwardly facing surfaces overlappingly joined to the exterior surfaces of the associated closure portion and a bead extending along said web to constitute a flexible support clampingly engaged by the associated row of interlocking links so as to hold them in a predeterminedly-spaced operatively-aligned relation, said bead being formed of an intermediate portion of the pre-formed sheet material of said web folded over a cord formation and united thereto to constitute a bead formation of a predetermined overall thickness determined by the thickness of the cord formation and the thickness of the pre-formed sheet material folded therover, said cord formation being substantially nonstretchable and the exterior of the folded-over elastic sheet portion overlying said cord formation embodying longitudinally extending elements exhibiting sufficiently greater longitudinal stretch resistance than the adjacent elastic sheet portion that the bead formation constitutes a substantially nonstretchable support effective in holding the links clamped thereto in their predeterminedly-spaced relation notwithstanding the stretchable character of the material of the folded-over sheet portion, and substantially preventing disturbance of the oper-

5   atively-aligned relation of associated links under the action of forces exerted thereon by the motion of the slider when locking or separating the links, the materials of said web and the material of said closure portions having similar elastic and bonding characteristics, and the facing portions of said web and said closure portion being united to each other over a continuous junction area so that the region of the junction 10 between the web and the closure is formed of material having substantially the same characteristics.

7. In a separable slide fastener for two closure portions having two cooperating rows of interlocking links which are brought into locking engagement and separated by a slider engaging said interlocking links, a stringer for each row of interlocking links forming the junction between the interlocking links and the associated closure portion, each stringer including an elongated web of pre-formed elastic stretchable rubber-like sheet material and a bead extending along said web to constitute a flexible support clampingly engaged by the associated row of interlocking links so as to hold them in a predeterminedly-spaced operatively-aligned relation, said bead being formed of a portion of the pre-formed sheet material of said web folded over a cord formation and united thereto to constitute a bead formation of a predetermined overall thickness determined by the thickness of the cord formation and the thickness of the pre-formed sheet material folded thereover, said cord formation being substantially nonstretchable and the exterior of the folded-over elastic sheet portion overlying said cord formation embodying longitudinally extending elements exhibiting sufficiently greater longitudinal stretch resistance than the adjacent elastic sheet portion that the bead formation constitutes a substantially nonstretchable support effective in holding the links clamped thereto in their predeterminedly-spaced relation notwithstanding the stretchable character of the material of the folded-over sheet portion, and substantially preventing disturbance of the operatively-aligned relation of associated links under the action of forces exerted thereon by the motion of the slider when locking or separating the links.

50 8. In a separable slide fastener for two closure
portions having two cooperating rows of inter-
locking links which are brought into locking en-
gagement and separated by a slider engaging
said interlocking links, a stringer for each row
55 of interlocking links forming the junction be-
tween the interlocking links and the associated
closure portion, each stringer including an elong-
ated web of pre-formed elastic stretchable rub-
ber-like sheet material forming two portions
60 having inwardly facing surfaces and a bead ex-
tending along said web to constitute a flexible
support clampingly engaged by the associated
row of interlocking links so as to hold them in a
predeterminedly-spaced operatively-aligned re-
lation, said bead being formed of an intermediate
65 portion of the pre-formed sheet material of said
web folded over a cord formation and united
thereto to constitute a bead formation of a pre-
determined overall thickness determined by the
thickness of the cord formation and the thick-
70 ness of the pre-formed sheet material folded
thereover, said cord formation being substan-
tially nonstretchable and the exterior of the
folded-over elastic sheet portion overlying said
75 cord formation embodying longitudinally extend-

ing elements exhibiting sufficiently greater longitudinal stretch resistance than the adjacent elastic sheet portion that the bead formation constitutes a substantially nonstretchable support effective in holding the links clamped thereto in their predeterminedly-spaced relation notwithstanding the stretchable character of the material of the folded-over sheet portion, and

substantially preventing disturbance of the operatively-aligned relation of associated links under the action of forces exerted thereon by the motion of the slider when locking or separating 5 the links.
